POLISHING BLOCK

James Green, Brackenridge Heights, Pa., assignor to Pittsburgh Plate Glass Company, Allegheny County, Pa., a corporation of Pennsylvania

Application October 20, 1937, Serial No. 169,982

6 Claims. (Cl. 51—197)

The present invention relates to apparatus employed in the surfacing of plate glass and more particularly to an improved form of polishing block for use in such operation.

5 The primary object of my invention is the provision of a new style of polishing block, the use of which effects a great increase in the life of felts combined therewith to carry the polishing rouge, a material increase in the rate of polishing and 10 a general improvement in operating efficiency.

10 This and other objects and advantages of my invention will become more apparent during the course of the following detailed description.

Briefly stated, my invention contemplates the 15 use of a polishing block having the working surface thereof scored in suitable pattern as a carrier for the polishing felt.

The polishing of plate glass, after the rough 20 irregularities have been ground away by the application of coarse abrasives, is largely effected by rouge or other finely divided abrasive in the form of a water slurry. This rouge is pressed against the surface of the glass by a felt pad secured upon the face of a revolving polishing 25 block. The polishing blocks have heretofore been provided with a smooth working face in order that they would have a uniform bearing surface for the felt pads. In such construction, however, the felt pads have a relatively short life 30 span and it is also necessary to replace them before they are completely used to avoid possible damage of the plate glass being polished.

The present invention involves the discovery 35 that by scoring the working surface of the polishing block with a number of grooves, pits, or other suitable depressions, the life of the polishing felts is increased several fold and at the same time the number of blocks necessary to the polishing operation is reduced by approximately 40 fifty per cent.

In the drawings forming a part of this application and wherein like numerals are employed to designate like parts throughout the same:

Figure 1 is a transverse sectional view of a 45 polishing block with a felt layer positioned thereon, taken substantially along the line I—I of Figure 2.

Figure 2 is a bottom plan view of one form of polishing block embodying my invention.

50 Figure 3 is a bottom plan view of a modified form of polishing block.

Figure 4 is a fragmentary sectional view on an enlarged scale taken substantially along the line IV—IV of Figure 3, showing a layer of felt in 55 position upon the block.

As shown in the drawings, a polishing block 1 of steel or cast iron is suspended upon the lower end of a vertical spindle 2 by means of a universal ball and socket joint 5 that not only permits rotation of the block 1 about the spindle 2, 5 but also allows the block 1 to adjust itself to the plane of the surface of the glass being polished. A clamping plate 6 secured to the block 1 by bolts 7 maintains proper relationship between the block 1 and the spindle 2. Usually a plurality of 10 blocks are mounted upon a rotatable spider which is positioned directly above the plate glass conveying apparatus. The specific form of the spindles, spiders and conveyors, however, is conventional and need not be described in detail. 15

The working surface of the polishing block 1 is scored to provide a plurality of parallel grooves 8, intersected by a second set of mutually parallel grooves 9 to provide prominences 10 of regular shape extending substantially over the entire 20 surface of the block 1. A larger prominence 11 is left in the center of the working surface in order that the block 1 be not excessively weakened at the ball and socket joint 5. The working surface of the block 1 is bevelled at the edges 15 25 to permit a polishing felt 16 to be placed thereon without undue stress at the periphery. The polishing felt 16 as shown in Figures 1 and 4, covers or extends across the depressions or scorings and is held in position upon the block 1 by 30 means of a clamping ring 17 abutting shoulders or lugs 18 projecting from the block 1. If desired, the polishing felt 16 may be cemented to the block 1 to eliminate the use of the annular ring 17 or similar clamping device. 35

Figures 3 and 4 illustrate a modification in which the working surface of the polishing block is provided with a plurality of recesses 20 of circular form arranged in a regular pattern. The other features of the block are identical with the 40 block previously described.

The particular arrangement of the grooves or recesses is not of major importance to the success of my invention and instead of intersecting parallel grooves 8 and 9, a single spiral groove 45 may be provided upon the working surface of the block 1 with equally advantageous results.

The mode of operation of the improved polishing blocks as provided by my invention is essentially the same as that of the conventional 50 smooth blocks. It has been found, however, that in operation this new style of polishing block increases the effective life of the polishing felts carried thereon by approximately three hundred per cent. This feature alone obviates the fre- 55

quent renewal of the polishing felts, thus reducing the maintenance cost of the polishing operation.

In a series of tests, polishing felts carried by blocks formed in accordance with the provisions of the present invention ran for an average period of eighteen hundred hours before failure while felts carried by conventional blocks having smooth working surfaces and operating under similar conditions ran for only six hundred hours. The reason for the phenomenal increase in the life of the felts is not at present clear. The results are the direct antithesis of what would normally be expected because it would naturally be assumed that the edges of the grooves or recesses in the polishing blocks would tend rapidly to wear away the felt layers along the lines of contact. Moreover, the reduction of the bearing surface of the blocks should apparently tend to increase the pressure upon the portions of the felt over the elevations of the surface of the blocks. Such increase in pressure would be expected to augment the wear upon the felts.

It is probable that as the felt 16 is pressed into the recesses portions of the working face of the polishing block, a large percentage of the rouge, employed to aid in the polishing operation, is drawn up into the felt and this action results in the more rapid formation of a face essential to the most efficient polishing. This face, or layer of rouge, is evenly distributed over the felt, thus eliminating the possibility of the formation of hard spots with other accompanying disadvantages. The heavier layer of rouge formed on the face of the felt results in better contact with the glass plates and accordingly a more rapid polishing is effected.

It has been found that the number of polishing blocks carried by the spiders may be reduced by half without impairment of the resulting polish. It will be seen, therefore, that by reducing the number of polishing blocks and by increasing the life of the polishing felts used thereon, the cost of felts for the polishing of plate glass is greatly lowered.

It is to be understood that the form of the apparatus herewith shown and described is susceptible of various changes and modifications

without a departure from the spirit or scope of my invention as set forth in the appended claims.

What I claim is:

1. In combination in apparatus for polishing glass plates, a metal polishing block, the working surface of which is scored to provide a plurality of depressions therein, a layer of resilient material adapted to receive a slurry of suitable abrasive covering the working surface of the block, and means for securing the layer of resilient material to the polishing block. 10

2. In combination in apparatus for polishing glass plates, a metal polishing block, the working surface of which is provided with a plurality of recesses arranged in a regular pattern, a layer of resilient material adapted to receive a slurry of suitable abrasive covering the working surface of the block, and means for securing the layer of resilient material to the polishing block. 15

3. In combination in apparatus for polishing glass plates, a metal polishing block having a grooved working surface, a layer of resilient material adapted to receive a slurry of suitable abrasive covering the working surface of the block, and means for securing the layer of resilient material to the polishing block. 20

4. In combination in apparatus for polishing glass plates, a metal polishing block, the working surface of which is scored with intersecting grooves, a layer of felt covering the working surface of the block, and means for securing the layer of felt to the polishing block. 25

5. In combination in apparatus for polishing glass plates, a metal polishing block, the working surface of which is scored with a set of parallel grooves, intersected by a second set of grooves, a layer of felt covering the working surface of the block, and means for securing the layer of felt to the polishing block. 30

6. In combination in apparatus for polishing plates, a polishing block of metal having portions of the working face thereof cut away to provide a scored surface and a covering of porous resilient material adapted to receive and hold a slurry of polishing rouge applied and secured directly to the working surface of the block and extending over the scorings. 40

JAMES GREEN.
